PUSH BUTTON SWITCH

Filed Sept. 4, 1928

UNITED STATES PATENT OFFICE

HENRY R. LIETZKE, OF SYRACUSE, NEW YORK, ASSIGNOR TO THE WARNER CORPORATION, OF SYRACUSE, NEW YORK, A CORPORATION OF INDIANA

PUSH-BUTTON SWITCH

Application filed September 4, 1928. Serial No. 303,802.

This invention relates to a new and improved push button switch and the method of assembling the same and has particular reference to the type of push button switch which is used with automotive signaling devices.

The usual signaling device used on an automobile is one which is electrically driven and one with which a switch is required so that the signal may be sounded as desired. The type of switch used with these devices is usually of a type which is normally held open by a spring the contact being made by pressing down a button against the action of the spring.

The usual place for attaching the switch is on the top of the steering column of the vehicle and the usual method of assembling this type of push button switch has been to insert the button through a counter sunk hole in the top plate on the steering column, the button carrying a flange to limit its upward movement. With this method of assembly the diameter of the button is necessarily limited by the size of the hole which can be made in the top plate, and the main object of my invention is to devise a switch structure and a method of assembling the same which will permit the use of a button of any desired diameter irrespective of the size of the hole in the top plate.

Other objects and advantages relate to the size, shape and arrangement of parts and the method of assembling the same all as will more fully appear from the following description taken in connection with the accompanying drawings, in which:

Figure 1 is an elevation partially in section and partially broken away of the upper end of a steering column with my device in position.

Figure 2 is a perspective view of the improved push button.

Figure 3 is a section on line 3—3 of Figure 1.

Figure 4 is a perspective view of the push button retaining member.

Figure 5 is a section on line 5—5 of Figure 1.

The push button —1— has a body portion —2— of the usual circular shape and carries

a depending tubular skirt —3— of a material of high conductivity. The skirt —3— has a plurality, in this case shown as four, of outwardly extending spaced tongues —4— forming approximately right angles to the main body of the skirt —3—. The push button retaining member —5— consists of a circular disc having a central circular aperture —6—. The walls of aperture —6— are provided with a plurality, in this case shown as four, of inwardly extending U-shaped bosses —7— in spaced relation. The slots —8— in the bosses —7— are of a width to receive tongues —4— and the adjacent bosses —7— are spaced from each other a distance which permits the passage between them of tongues —4—.

I also provide a circular base member —9— having a depending collar —10— adapted to be countersunk into the hub —11— of the steering wheel —12—. The upper portion of base member —9— is of a size and shape to register with the push button retaining member —5—.

There is usually provided on the top of the steering wheel —12— operating levers —13— and —14— for the control of the spark and throttle of the vehicle and I have here shown such lever in position between push button retaining member —5— and base member —9— altho such levers need not necessarily be assembled as indicated and may if desired be eliminated entirely. An insulated wire —15— leading from a source of potential, not shown, is positioned inside of the steering post 16. Wire —15— has its upper end secured in an insulated post —17— which post —17— is supported on a base —18—. The insulation is removed from the end of wire —15— and the exposed wire is placed in electrical connection with a contact post —19— on the upper end of post —17—.

When it is desired to place my device in position switch button —1— is assembled in switch button retaining member —5— by inserting tongues —4— in the spaces between bosses —7— and moving them downwardly until they extend beyond the end of bosses —7— so that switch button —1— may be rotated in relation to switch button retaining

member —5— until the tongues —4— come into registration with slots —8— at which time switch button —1— is moved upwardly until tongues —4— engage the bottom of slots —8— thereby limiting any further outward movement of switch button —1— from switch button retaining member —5—.

With levers —13— and —14— in position on base member —9— and with base —18— in position on the upper surface of lever —14— I place a circular spring —20— around post —17—. I then place switch button retaining member —5— on the upper surface of lever —14— and I then secure base —9—, levers 13 and 14 and switch button retaining member —5— securely together by means of screws —21—. As may best be seen from Figure 3 levers —13— and —14— are provided with slots —22— so that they may be rotated with reference to the other parts of the assembly. Collars —22'— are provided so that push button retaining member —5— and base —9— will be held in spaced relation and levers —13— and —14— will not be bound against rotation. When the parts have been assembled together base —9— is positioned in hub —11— of the steering wheel —12—.

The length of spring —20— is such that it presses against push button —1— and normally holds it upward with tongues —4— against the bottom of slots —8— and with tubular skirt —3— in spaced relation with contact post —19—. The relation of parts is such, however, that push button —1— may be depressed against the action of spring —20— until the tubular skirt —3— comes in contact with the post —19— to complete the electrical circuit to the signaling device, not shown, and tubular skirt —3— will contact with post —19— before tongues —4— leave slots —8— so that they cannot be brought into registration with the passageways between bosses —7— to permit switch button —1— to be removed from switch button retaining member —5—.

The tubular skirt —3— is as stated of a material of high electrical conductivity as is also the switch button retaining member —5— and inasmuch as the switch button retaining member —5— is an electrical connection to levers —13—, —14— and base —9— and the steering column —16— which in turn is in electrical connection with the main body of the vehicle the bringing together of tubular skirt —3— and post —19— will complete the electrical circuit from the source of potential to the ground.

It will be understood that altho I have shown my push button switch in position on the steering post of an automobile it may be positioned on any part of the vehicle which may be considered desirable and it will also be understood that altho I have shown my device as used with a signaling device on an

automotive vehicle it may be used for any purpose where a normally open push button switch is desired, for altho I have shown and described a specific structure and form of part as an exemplification of an embodiment of my invention I do not desire to restrict myself to the exact size, shape or arrangement of parts as various changes may be made within the scope of the appended claims.

What I claim is:

1. In a device of the class described, a push button having a depending flange with laterally extending spaced ears, a push button retaining member having a central aperture, inwardly extending spaced U-shaped bosses in said central aperture said bosses having slots in their lower ends open at the bottom and means for yieldingly holding the ears on the push button in the slots in the U-shaped bosses.

2. In a device of the class described, a push button having a depending flange with laterally extending spaced ears, a push button retaining member having a central aperture, inwardly extending spaced U-shaped bosses in said central aperture, said bosses having slots in their lower ends open at the bottom, means for yieldingly holding the ears on the push button in the slots in the U-shaped bosses, and an electrical contact post normally in spaced relation to the push button.

3. In a device of the class described, a push button having a depending flange with laterally extending spaced ears, a push button retaining member having a central aperture, inwardly extending spaced U-shaped bosses in said central aperture said bosses having slots in their lower ends open at the bottom, an electrical contact post normally in spaced relation to the push button, and spring means for holding the electrical contact post and the push button in such spaced relation with the ears on the push button positioned in the bosses in the slots in the push button retaining member.

4. In a device of the class described, a push button provided with a plurality of spaced radially extending flanges and a retaining member for said push button having a central aperture and recesses in the wall bordering said aperture within which said radial flanges are positioned said wall having longitudinally extending open ended slots intermediate said recesses, and spring means maintaining said parts in assembled position.

In witness whereof I have hereunto set my hand this 31 day of August, 1928.

HENRY R. LIETZKE.
